UNITED STATES PATENT OFFICE.

JOSEPH W. BRANDENBURG, OF DAYTON, OHIO.

BURIAL-VAULT.

SPECIFICATION forming part of Letters Patent No. 769,587, dated September 6, 1904.

Application filed November 7, 1903. Serial No. 180,229. (No model.)

To all whom it may concern:

Be it known that I, JOSEPH W. BRANDENBURG, a citizen of the United States, residing at Dayton, in the county of Montgomery and State of Ohio, have invented new and useful Improvements in Burial-Vaults, of which the following is a specification.

My invention relates to new and useful improvements in burial-vaults; and its object is to provide a structure of this character the parts of which can be readily removed and secured together to form an air and water proof device which is practically indestructible as a result of the action of moisture or various climatic conditions.

The invention consists in providing a vault formed, preferably, of three parts which are molded into proper shape and which are adapted to be readily assembled within a grave and which will be firmly held together by securing means provided for the parts.

The invention further consists in forming each section of a combination of metal and cement, whereby the device may be rendered more lasting.

The invention also consists in the further novel construction and combination of parts hereinafter more fully described and claimed, and illustrated in the accompanying drawings, showing the preferred form of my invention, and in which—

Figure 1 is a longitudinal section through the vault, one wall thereof being broken away and showing the arrangement of the metal therein. Fig. 2 is a horizontal section through the vault, and Fig. 3 is a section on line 3 3, Fig. 2.

Referring to the figures by numerals of reference, 1 is the base of the vault, the same being formed of cement, in which is embedded a width of wire-netting 2, which serves to bind the cement together and prevent the base from breaking into two or more parts. A flange 3 extends upward from each end and side of the base, and within the side flanges are embedded longitudinally-extending rods 4, having right-angular extensions 5 at their ends, which project into the end flanges. Similar rods 6 are arranged in said end flanges

and have right-angular extensions 7 at their ends, which project into the side flanges 3 at points between the rods 4. Retaining-pins 8, formed of any suitable material, are arranged upon the flanges 3 and are adapted to project into recesses 9, formed in the lower edges of the side and end walls 1 and 10, respectively. These four walls are formed in a single piece and are constructed of cement or other equivalent material in which are embedded rods 11 and 12, which are similar in form to the rods 4 and 6, heretofore referred to. The upper faces of the walls 10 are cut away at their inner edges to form recesses 13, which receive the edges of a cover 14. This cover is of any suitable contour and is formed of cement or other equivalent material in which is embedded a wire-netting 15, which serves to bind the cement and prevent the same from breaking. Handles 16, formed of metal or other material, extend from the cover 14, whereby the same may be readily raised or lowered. Similar handles 17 also extend from the sides of the detachable walls.

After a grave has been dug the base 1 of the vault is placed therein, and the walls 10 are then lowered, so as to permit the pins 8 to project into recesses 9. The meeting edges of the walls 10 and the flanges 3 may then be sealed together by means of a suitable cement, (not shown,) and the vault is then ready for use. The cover 14 can be readily lowered into position with its edges in the recesses 13, and after it has been properly placed cement or other material may be molded over the adjoining edges of the cover and the walls 10, thereby thoroughly sealing the vault against the admission of air or moisture.

In the foregoing description I have shown the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is—

A device of the character described having

a base and walls formed of cement, rods embedded within and extending longitudinally of the sides and ends of the device, the ends of the rods having right-angle extensions and 5 adapted to overlap at the corners of the device, and a cover for the device formed of cement and having netting embedded therein.

In testimony whereof I affix my signature in presence of two witnesses.

JOSEPH W. BRANDENBURG.
